CLAIM

The ornamental design for a breakout for cable assembly, as shown and described.

DESCRIPTION

FIG. 1 is a perspective view of a breakout for cable assembly, showing my new design;

FIG. 2 is a side view of the breakout for cable assembly shown in FIG. 1; and,

FIG. 3 is a top view of the breakout for cable assembly shown in FIG. 1.

The broken lines showing cable lines in FIGS. 1 through 3 are for illustrative purposes only and form no part of the claimed design.
